JAMES C. DUNCAN, OF OLNEY, ILLINOIS, ASSIGNOR TO HIMSELF AND
J. B. ALEXANDER, OF WASHINGTON, DISTRICT OF COLUMBIA.

Letters Patent No. 64,648, dated May 14, 1867.

PORABLE FENCE.

The Schedule referred to in these Letters Patent and making part of the same.

TO ALL WHOM IT MAY CONCERN:

Be it known that I, JAMES C. DUNCAN, of Olney, in the county of Richland, and State of Illinois, have invented a new and useful improvement in Portable Fences; and I do hereby declare the following to be a full, clear, and exact description of the same, reference being had to the accompanying drawings which are made part of this specification, and in which—

Figure 1 is an end elevation of my improved fence.

Figures 2 and 3 are side elevations.

Figure 4 is a detached view.

Similar letters of reference indicate corresponding parts in the several figures.

The object of my invention is to obtain a simple, cheap, and durable fence, which can be built or put up with facility, and which shall not be liable to injury from shrinkage. To this end it consists in a novel construction of trestle or support for sustaining the ends of the lumber, rails, or poles which make up the fence, which may be either a field, stock, or other enclosure.

In order that others skilled in the art to which my invention appertains may be enabled to fully understand and use the same, I will proceed to describe it in detail.

In the drawings, A may represent flat lumber rails, but instead thereof the ordinary split rails or poles may be employed. The ends of the rails A are confined between the upright parallel battens C C, which are connected together by the transverse pins D and keys d, the ends of the rails resting on the pins D, as represented in fig. 4. Each pair of battens C C is supported laterally by means of the converging braces E E, the upper ends of which are secured to the battens by one of the pins D which support the rails. The lower ends of the braces E E extend below the fence, and are suitably embedded in the ground to give steadiness and rigidity to the fence laterally. A cross-tie or bar, F, connects the lower ends of the braces to the battens, as represented in fig. 1. The supporting trestles, constructed as above described, are braced and steadied asunder by notching the ends of one of the rails, say the upper one, so as to cause the same to engage over its supporting pins D, (see fig. 4.) The lower rail may rest upon the ground or be sustained a little above the same by a block or stone.

The trestles above described can be manufactured cheaply, and with their aid the fence can be set up with great facility. A fence thus built is durable, not being liable to shrinkage, and the material of the structures may be produced in various ways, as by sawing or splitting. The number of rails may be varied as represented in the drawing. The entire structure may be built without the use of sawed timber, as the material generally found in the hands of the farmer will suffice.

I do not claim the battens C C, braces E E, or pins D D, separately considered, as I am aware that these points in themselves are not new.

Having thus described my invention, what I claim as new herein, and desire to secure by Letters Patent, is—

The supporting trestle, consisting of the battens C C, braces E E, pins D, rails A, and cross-tie F combined substantially in the manner and for the purpose specified.

JAMES C. DUNCAN.
